JAMES HENRY YOUNG, OF BRONX, NEW YORK, ASSIGNOR TO THOMAS C. WILSON, INCORPORATED, OF NEW YORK, N. Y., A CORPORATION OF NEW YORK

TUBE CLEANER

Application filed June 30, 1931. Serial No. 547,873.

This invention is concerned with devices for cleaning tubes and the like and particularly with rotary cleaners for removing scale from boiler tubes.

5 The devices commonly used for cleaning boiler tubes comprises a body which is rotated and moved through the tube by a rod or equivalent means upon the end of which it is fastened. On this body are cutters 10 which contact with the walls of the tube to cut the scale or other foreign matter therefrom. While these cutters may be rigidly fixed to the body of the tool, it is customary not to so fix the cutters but to attach the 15 cutters to the tool so that they may move outwardly to adjust themselves to the size of tube and thus permit cutters on all sides of the tool to operate on the walls of the tube at the same time.

20 The cutters are usually urged outward against the tube by centrifugal force and in order to allow this movement the cutters are generally carried on arms pivoted to the body member. These arms may swing about 25 an axis perpendicular to the axis of the tube or they may swing about an axis parallel to the axis of the tube.

This invention is particularly concerned with the type of device in which the cutters 30 are mounted on arms pivoted about axes which are perpendicular to the axis of the tube, although certain principles of this invention apply as well to devices of other types.

35 The object of the invention is to provide a tube cleaner which operates with a highly effective cleaning action and which is cheaper and easier to construct, more durable, and simpler to assemble and take apart for repair and replacement purposes than the devices as heretofore constructed.

In one form of embodiment of the principles of my invention, the device comprises a body to be mounted on the end of a drive shaft, a plurality of arms mounted on fulcrum surfaces in the body for limited pivotal movement and provided with shafts on which cutters are loosely mounted, and a collar which receives a portion of the body and operates to hold the arms against their

fulcrum surfaces and to limit the pivotal movement thereof. The collar is held in place on the body by the shaft when the device is attached to the shaft and upon removal of the device the collar may be readily slipped 55 free, thus releasing the arms. The fulcrum surfaces in cooperation with the collar serve the additional purpose of locking the arms and cutter shafts against endwise movement and with this arrangement, the device can 60 be cheaply constructed since it requires little machining.

For a detailed description of the preferred form of device employing the principles of this invention, reference may be 65 had to the accompanying drawing, in which Fig. 1 is a side view in section of one form of this invention;

Fig. 2 is a side view in section of the same 70 form of invention, but the section is taken at right angles to the section in Fig. 1;

Fig. 3 is an end view of the device shown in Fig. 1, with the device in position in a boiler tube;

Fig. 4 is a sectional view of Fig. 1 taken 75 on the line 4-4;

Fig. 5 is a side sectional view of a modified form of this invention in which there are four cutter arms pivoted to the body;

Fig. 6 is a sectional view of the device 80 shown in Fig. 5, taken along the line 6-6;

Fig. 7 is an enlarged sectional view of one of the cutter arms showing the cutter shaft and cutter in position;

As illustrated in Figs. 1 to 4 of the drawing, the preferred form of this invention consists of a body 10 having a slot 11 extending across it and inwardly from one end. The body 10 is bored at 12 so that it receives a retaining pin 13 which crosses the slot 11, 85 at right angles. Arms 14 and 15 are also received in the slot 11, one of these arms lying on each side of the pin 13. The arms are each bored longitudinally to receive cutter shafts 16, each of which extends beyond 90 the end of its arm and is provided with a head 17 and a rotary cutter 18 which is carried loosely upon the cutter shaft between the head and the outer end of the arm.

Each of the arms has a cut-out portion 19, 100

into which the pin 13 fits and the shafts 16 have corresponding cut-out portions 20 which also surround a part of the pin 13. When the arms 14 and 15 are held against the pin 13 so that the openings therein surround a part of the pin and so that the openings in the shaft also surround a part of the pin, the shaft is held within the arm so that it cannot move endwise. The arms are free, however, to swing about the pin as a pivot, and the pin, accordingly, serves as a fulcrum member or surface.

In order that the cut-out portion in the shaft 16 may easily be turned toward the pin 13, a flat side 21 is provided on the head 17 of the shaft 16 on the same side as the cut-out portion 20. Thus by merely turning the flat side of the head towards the side on which the pin lies, the cut-out portion 20 may be brought to register with the pin 13.

To hold the arms 15 and 16 against the pin 13, a cup-shaped retainer collar 23 fits around the body 10 and encloses a part of the arms 14 and 15 where they lie within the slot 11. The outer sides of the arms 14 and 15 are cut away at 24 where they contact with the ring 23, so that the arms may pivot through a limited angle about the pin 13 as a fulcrum while still remaining substantially in contact both with the pin and with the retaining collar. This allows the pivoting movement of the arms, while preventing the ends of the arms from rattling back and forth, and thus causing the noise commonly known as "chattering", with attendant wear and destruction of the tool. The cup-shaped retainer ring completely surrounds one end of the body 10, but is provided with a hole 26 through which a threaded end of a drive shaft 27 passes into a threaded recess 28 in the body 10. A shoulder 29 on the drive shaft bears against the cup-shaped retainer collar and holds it rigidly against the body when the drive shaft is screwed into place.

The two cutter arms 14 and 15 are preferably of different lengths in order that the cutters may be laterally spaced apart in the tube. The arm 14 is provided with a recess 30 in which one edge of the cutter 18 on the arm 15 may lie. A pin 31 in the body 10 passes perpendicularly through the slot 11 near its outer end. This pin passes between the arms 14 and 15 which are cut out around it and the pin serves to strengthen the body and to limit the movement of the cutter arms during assembly and the like.

In the modified form of this device, as described in Figs. 5 and 6, the body 40 comprises a cylindrical portion 41 having a threaded recess 42 in one end thereof, and a drive shaft 43 threaded into the recess. At the other end of the cylindrical portion 41 the body 40 has a tapered portion 44 sur-

mounted by a square section 45. Pin members 46 are mounted in the surfaces of the square portion so that they form a square surrounding the portion 45 and extend outwardly therefrom. These pin members may be separate from the body, or they may be an integral part thereof. Cutter arms 47 and 48 lie against the pins 46 and have cut-out portions 49, each of which surrounds a part of a pin 46 whereby the arm may pivot about the pin, the pin thus serving as a fulcrum member or surface. Each of the arms 47 and 48 is bored to receive a cutter shaft which carries a cutter as already described. A retainer collar 50 surrounds a part of the body and holds the arms in place as described in reference to Figs. 1-4.

In this modification the opposite arms 47 are shorter than the opposite arms 48 and the arms 48 are cut out at 51 so that they will not strike the cutters on the arms 47. A feeler rod 52 is received in a threaded opening 53 in the body and this rod extends beyond the tool so as to contact with the header end of the tube or with an elbow in the tube and thus prevents the tool from being pushed through into a header or against an elbow.

Having thus described my invention, what I claim is:

1. A tube cleaner which comprises a body, a fulcrum member mounted in the body, an arm having a recess formed in one of its surfaces, said arm contacting with said member with the latter entering the recess and providing a fulcrum on which the arm may rock, a shaft mounted in a bore through the arm, a cutter on the shaft, the shaft having a portion engaged by the fulcrum member to prevent endwise movement of the shaft, and a retaining collar on the body overlying a portion of the arm and preventing its removal from the fulcrum member while permitting the arm a limited degree of pivotal movement with reference to the fulcrum member.

2. A tube cleaner which comprises a body, a fulcrum member mounted in the body, an arm having a recess formed in one of its surfaces, said arm contacting with said member with the latter entering the recess and providing a fulcrum on which the arm may rock, a shaft mounted in a bore through the arm, said recess intersecting the bore, said shaft having a cut-out portion in registry with said recess and in which a part of said fulcrum member lies whereby said fulcrum prevents endwise movement of the shaft, and a cutter mounted on the shaft.

3. A tube cleaner which comprises a body having a slot therein, a pin in said slot, an arm lying with one surface against the pin, said pin constituting a fulcrum on which said arm may rock, said arm having a bore therethrough and a lateral opening to said bore, said opening being closed by said pin,

a shaft mounted in the bore through the arm and having a portion engaged by the pin to prevent endwise movement of the shaft, and a cutter on the shaft.

4. A tube cleaner which comprises a body having a slot therein, a pin in said slot, an arm resting against the side of said pin and fulcrumed thereon, said arm being freely removable from said pin while the latter remains in place in the slot, a shaft mounted in a bore through the arm and having a portion engaged by the pin to prevent endwise movement of the shaft, a cutter on the shaft, and a retaining collar on the body overlying a portion of the arm and preventing its removal from the pin.

5. A tube cleaner which comprises a body, a pin mounted transversely in said body, an arm, a shaft mounted in a bore through the arm, a cutter on the shaft, said arm and said shaft both having portions cut away to fit the surface of the pin, said arm resting against the side of the pin with the latter entering the recesses formed in the arm and shaft, the arm being fulcrumed on said pin and said shaft being prevented from moving endwise by the pin, and a retaining collar on the body overlying a portion of the arm and preventing its removal from the pin but permitting the arm a limited degree of pivotal movement about the pin.

6. A tube cleaner which comprises a body, a pin mounted transversely in said body, an arm, a shaft mounted in a bore through the arm, a cutter on the shaft, said arm and said shaft both being cut out to fit around a part of said pin whereby said arm may pivot about the pin and said shaft is prevented from endwise movement and a retaining collar on the body overlying a portion of the arm and preventing its removal from the pin but permitting the arm a limited degree of pivotal movement about the pin, said body having an opening to receive a driving shaft, a driving shaft in said opening, and said retaining collar comprising a cup-shaped member having a hole therein through which said driving shaft passes, said driving shaft having a shoulder bearing against said collar to clamp the collar against the body.

7. A tube cleaner which comprises a body, a retaining pin mounted in said body, an arm pivotally mounted on said pin, a shaft mounted in a bore through the arm and having a portion engaged by the pin to prevent endwise movement of the shaft, a cutter on the shaft, a driving shaft connected to one end of said body and a feeler rod threadedly connected to the other end of said body.

8. A tube cleaner which comprises a body having a slot therethrough, an arm mounted in each end of said slot, a shaft mounted in a bore through each of said arms, a cutter on each shaft, a retaining pin mounted in said

body and passing through said slot between said arms, each of said arms and said shafts having cut-out portions which surround a part of said pin whereby the arms may pivot about the pin and the shafts are secured against endwise movement, and a retaining collar holding said arms against said pin.

9. A tube cleaner which comprises a body, arms, a shaft mounted in a bore through said arms, a cutter on each shaft, a retaining pin mounted in said body, said arms and said shafts having cut-out portions which surround a part of said pin whereby the arms may pivot about the pin and the shafts are secured against movement, and a retaining collar holding said arms against said pin, one of said arms being longer than the other of said arms, said longer arm having a cut-out portion within which a part of the cutter mounted on said shorter arm may lie.

10. A tube cleaner which comprises a body having a slot therethrough, an arm mounted in each end of said slot, a shaft mounted in a bore through each of said arms, a cutter on each shaft, a retaining pin mounted in said body and passing through said slot between said arms, each of said arms and said shafts having cut-out portions which surround a part of said pin whereby the arms may pivot about the pin and the shafts are secured against endwise movement, a retaining collar holding said arms against said pin and means for securing said retaining collar in place.

11. A tube cleaner comprising a body, a retainer pins in said body forming a rectangle, an arm mounted on each of said pins, a shaft mounted in a bore through each of said arms, each of said shafts and said arms having a cut-out portion to fit around a part of one of said pins whereby the arm may pivot around the pin and the shaft is held against longitudinal movement, a cutter on said shaft and means for retaining said arm and shaft against said retaining pin, comprising a cup-shaped retaining collar surrounding a part of said body and a part of said arms, and a driving shaft passing through said retaining collar and being fastened to said body, said shaft having a shoulder thereon bearing against said collar to clamp the collar against the body.

12. A tube cleaner comprising a body, retainer pins in said body in the form of a rectangle, an arm in each end of each of said slots, a shaft mounted in a bore through each of said arms, each of said shafts and said arms having a cut-out portion to fit around a part of one of said pins whereby the arm may pivot around the pin and the shaft is held against longitudinal movement, a cutter on said shaft and means for retaining said arm and shaft against said retaining pin, one pair of opposite arms being longer than the other pair of opposite arms, said longer pair of arms having cut-out portions therein in

which the cutters on the shorter arms may lie.

13. A tube cleaner comprising a body, retainer pins in said body forming a rectangle, an arm mounted on each of said pins, a shaft 5 mounted in a bore through each of said arms, each of said shafts and said arms having a cut-out portion to fit around a part of one of said pins whereby the arm may pivot around the pin and the shaft is held against longitudinal movement, a cutter on said shaft and means for retaining said arm and shaft against said retaining pin, one pair of opposite arms being longer than the other pair of opposite arms, said longer pair of arms 10 having cut-out portions therein in which the cutters on the shorter arms may lie, and a feeler member threaded into said body.

14. A tube cleaner comprising a body provided with a fulcrum surface, an arm bearing against the fulcrum surface, a shaft 20 mounted in a bore in the arm and having a portion engaging the surface, said arm and said shaft having recesses formed by cutting away portions thereof, with said surface received in said recesses, and a collar mounted on the body and having a portion overlying the fulcrum surface, said portion of the collar preventing lateral bodily movement of the arm, and the engagement of the 25 arm and shaft with the surface preventing endwise movement of the arm and shaft.

15. In a tube cleaner, the combination of a body having a fulcrum surface, an arm having a recess formed in one surface thereof, 30 said arm resting against said surface with a portion of the latter received in said recess, and a member on said body overlying said arm and preventing disengagement of the arm from said surface while permitting the 35 arm to rock on said surface to a limited degree.

16. In a tube cleaner, the combination of a body having a fulcrum surface, an arm having a recess formed in a surface thereof, 40 said arm resting against said surface with a portion of said surface received in said recess, and a collar on said body overlying the arm adjacent its point of contact with the surface, said collar preventing disengagement of said arm from said surface while permitting said arm to rock on said surface to a limited degree.

17. In a tube cleaner, the combination of a body having a fulcrum surface, an arm having a recess formed in a surface thereof, said arm resting against said surface with a portion of said surface received in said recess, a shaft disposed in a bore in said arm having 50 a portion lying outside said bore, a cutting tool on said portion of the shaft, and a member on said body overlying a portion of the arm adjacent its point of contact with said surface, said member preventing disengagement of said arm from said surface while

permitting said arm to rock on said surface to a limited degree.

18. In a tube cleaner, the combination of a body having a fulcrum surface, an arm having a recess formed in a surface thereof, a bore 70 in said arm intersecting said recess, a shaft in said bore having a recess formed therein by removal of material, said recess registering with the recess in said arm and said arm contacting with said fulcrum surface with a portion of said surface received in the recess in said arm and the recess in said shaft, and a member on said body overlying at least a portion of said arm adjacent said fulcrum surface, said member preventing disengagement 75 of said arm from said surface while permitting said arm to rock on said surface to a limited degree.

In testimony whereof I affix my signature.
